LOCK OPERATING MEANS

Herman W. Voges, Springfield, Mass.

Application April 13, 1934, Serial No. 720,429

20 Claims. (Cl. 70—9)

This invention relates to improvements in lock operating means.

The principal objects of the invention are directed to the provision of an unlocking device.

5 According to the invention an actuating member of a lock receives a series of certain impulses from the unlocking device so that the bolt of the lock is released.

According to a special feature of the invention 10 a plurality of locks may be arranged to require series or trains of related impulses to release the bolts thereof and the unlocking device of the invention is arranged to impart the several different series or trains of impulses for the different locks. In this way, one unlocking device may be used with a number of different locks and set or adjusted to unlock each of the locks.

The objects of the invention are accomplished 15 by the provision of a novel combination and arrangement of parts, all as will more fully hereinafter appear in connection with the accompanying description of the present preferred form of the invention taken in connection with the accompanying drawing, wherein:

20 Fig. 1 is a longitudinal sectional view through the lock operating mechanism of the invention.

Fig. 2 is a transverse sectional elevational view on the line 6—6 of Fig. 1.

Fig. 3 is a fragmentary perspective view of one 25 of the key members of the device shown in Fig. 1.

Fig. 4 is a plan view of the guide member of the device.

Fig. 5 is a plan view of the forward end of the propeller.

30 Fig. 6 is a side elevational view of an end portion of the guide with the forward portion of the propeller associated therewith.

Fig. 7 is an enlarged plan view of the end portion of the guide with the forward end of the 35 propeller associated therewith.

Fig. 8 is a side elevational view showing a plurality of keys.

Fig. 9 is an elevational view to show how the cap may be registered with the body, and

40 Fig. 10 is a small scale plan view of the operating device associated with a lock.

Referring now to the drawing in detail the invention will be fully described.

I will first describe a lock mechanism embodying certain novel features of the invention and while the description refers particularly to a padlock, it will be understood that this is for purposes of description merely and that the broad features of the invention may well be embodied in locks 50 of all kinds. The parts to be described in con-

nection with the lock are shown in the drawing in their bolt-locking position.

In Fig. 1 there is shown a padlock having a casing 2 which is hollowed out and in the interior thereof are disposed the principal features of the novel lock mechanism. A shackle 4 has a side member 6 which is slidable in the casing. The lower end of the member 6 extends into the interior of the casing as shown while an arm or side member 8 is receivable in a suitable socket provided in the 10 casing when the shackle is in the locked position shown.

The notches 26 of the different tumblers may be spaced at different distances or angles from their respective shoulders 32. In this respect, the 15 tumblers may be different from one another. This is because it may be necessary to oscillate the tumblers more or less relative to one another in order to bring the notches into position to receive the lug 22 of the bolt 12. These tumblers 20 are moved counterclockwise by novel means, which will presently be described, to bring the notches thereof into an unlocking position wherein they receive the lug of bolt 12. As each of the tumblers is moved counterclockwise to bring its notch in 25 position to receive the lug of the lever 12, it is held in that position by its respective pawl 34.

A pilot 52 is oscillatable and reciprocable in the casing and is associated with a body 53 which carries an arm 56. A guide 54 has its upper end secured in the casing and its lower end is slidably received in a suitable bore of the body as shown so the pilot 52, body 53 and arm 56 may move back and forth and oscillate as well.

The arm 56 associated with the body in the 35 position shown in Fig. 1 has its outer end extending to the right of the body so that its extremity is adjacent the member 12, and clear of the tumblers.

The lock operating or unlocking device of the 40 invention as shown in the drawing preferably resembles a fountain pen in shape and size so that it may be conveniently carried in the pocket.

An inner barrel 70 and an outer cap 72 are arranged for sliding movements. As the cap is 45 moved on the barrel a plunger 74 extending from the outer end of the barrel, and which has already been referred to, is caused by mechanism associated with the cap and barrel to move outwardly and provide the impulses or strokes imparted to 50 the pilot of the lock for actuating the unlocking mechanism thereof.

The barrel preferably includes a head end 76, a body 78 which is bored out longitudinally to receive a guide member 90 and has radial slots ex- 55

tending longitudinally thereof terminating adjacent its ends for receiving keys 80 (see Fig. 2). An outer tube 80' overlies the keys.

The cap 72 is closed at its outer right-hand end 5 and its inner left-hand end slides on the barrel. A collar 82 is associated with the sleeve 80' which limits the rearward movement of the cap relative to the barrel.

The keys 80 as shown in Figs. 3 and 8 comprise a body portion 84 and flange portion 86, the former being receivable in the slots provided in the part 78 while the latter portions lie against the periphery of the part 78 and are inside the shell 80'. The keys have one or more spaced projections or cams 85, and as shown in Fig. 8, the cams on one key may be differently arranged than on another, all for the purpose which will later appear.

The guide 90 is slidable in the barrel and the pilot 74 previously referred to extends forwardly therefrom and is arranged for reciprocating movements in the outer end of the part 76. This guide is bored out so as to be tubular in form and has lower and upper longitudinally extending slots 92 and 94 which terminate adjacent the opposite ends of the guide. At either side of the upper slot parts of the guide are cut away to provide spaced lugs 93 having shoulders 96.

A hub 100 extends inwardly from the outer end of the cap 72 which is slotted as shown to receive an end portion of a propeller member 102 which is pivoted at 104 in said slot. A spring 104' is disposed within the cap between the inner end 116' of the barrel and end wall of the cap to urge the cap rearwardly of the barrel. The part 82 associated with the barrel acts in conjunction with a shoulder interiorly of the cap, to limit the separating movements of the barrel and cap, as shown in Fig. 1.

A relatively thin tongue 108 is provided on the forward end of the propeller which is slidable in the slots 92 and 94 of the guide so that as the cap is turned on the barrel the guide is turned therewith. A prong 110 is provided on the upper side of the propeller adjacent its forward ends which has inclined forward and rear faces 112 and 116. The main body of the propeller 102 is relatively wider or thicker than the tongue part 108 thereof so as to provide shoulders 114 extending transversely or up and down on either side thereof, just behind the tip of prong 110.

A recess 118 within the barrel at its right hand or inner end has an inclined surface, as shown, against which the surface 116 of the propeller may abut. The parts are shown in Fig. 1 with the cap in its rear position relative to the barrel in which position it is yieldingly held by the spring 104' with the inclined part 116 of the propeller seated on the inclined surface of the recess 118. In this position of the parts the cap, propeller and guide may be rotated relative to the barrel.

The prong 110 of the propeller 102 coacts with the cams 85 of the keys 80, as will presently appear, when the cap is moved forwardly of the barrel. A spring 120 anchored in the hub 100 has its forward end in yielding engagement with the propeller to urge the outer end of the propeller upwardly at all times.

As has been explained, the plunger 74 is inserted in the pilot bore with the outermost end of the barrel resting against the casing of the lock (see Fig. 10). Pressure of the plunger 74 to the pilot and associated parts is the initial movement or impulse for actuating the unlock-

ing mechanism of the lock. Further successive impulses or movements of the plunger with the end of the barrel against the lock casing are produced as the cap is moved forwardly of the barrel.

As the cap is moved forwardly to move the propeller 102 forwardly, the shoulder 114 of the propeller brings up against the shoulder 96 nearest the rear end of the guide 90 (see Figs. 6 and 7). The guide 90, from which extends 10 plunger 74, is propelled or moved forwardly by the propeller until the forward face 112 of the propeller prong 110 engages the innermost cam 85 of the key 80.

As the face of the prong brings up against the 15 cam of the key, the cam causes the end of the propeller to be depressed or swung downwardly so that the shoulder 114 of the propeller is disengaged from the shoulder 96 of the guide 90. This allows the guide and plunger to be moved 20 inwardly by means of spring 120 disposed in a recess 11 around the plunger 74 in the forward end of the barrel.

After the free end of the propeller is moved 25 downwardly by the key and while pressure is being applied to the cap the free end of the propeller is caused to move again upwardly at the other side of the cam 85 by the spring 120. The shoulder 114 is then behind the next adjacent shoulder 96 of the guide 90 so the propeller again propels the guide. Continued pressure on the cap carries the end of the propeller towards the next key so that it is again disengaged from the guide whereupon the guide jumps back and the shoulder of the propeller engages 35 a successive shoulder of the guide.

In the manner described, by pressing on the cap the guide and plunger are given successive forward movements or impulses. When the prong 110 of the propeller has passed the last 40 cam in the key, the forward shoulder 114 of the cap brings up against the inner or rear end of the guide so that the guide and plunger are moved by the cap for its final impulse or stroke.

It will be observed that as the cap is moved 45 forwardly of the barrel by endwise pressure when the end of the barrel rests against the lock casing, the plunger is caused to move outwardly and returned accordingly as the propeller engages the guide and is released therefrom.

The different distances through which the guide and plunger are moved by the propeller corresponds to the different distances between the cams of the key. The distance between the cams of a key may be varied within wide limits 55 so that the plunger may be caused to make a train of strokes wherein the strokes are of different lengths. As the cap is moved forwardly of the barrel the plunger is caused to make any desired number of strokes or impulses depending 60 on the number of cams on the key.

The keys as shown in Fig. 8 have the cams arranged thereon in different ways to provide trains of impulses varying widely in nature and there may be any desired number of keys employed. In the form of the invention shown in Fig. 2 there are 8, the lowermost key being omitted in Fig. 1 for clearness. The key shown in Fig. 1 is adapted for use in connection with the lock mechanism described. Where there are a number of locks, the locks may require for actuating their respective locking mechanisms a train of impulses which vary from one another and the unlocking device may have a plurality of keys ca- 75

pable of producing the proper trains of impulses for each of the locks.

The cap may be rotated on the barrel to bring the propeller into alignment with any certain key so that a certain train of impulses may be selected for a certain lock. The barrel may carry a plurality of characters 71 while the cap has an indicating means such as an arrow 73 for registering with the characters. This makes it possible to locate the cap so the propeller will act in conjunction with a selected key to produce a train of impulses of predetermined relative lengths and number.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

1. A device for operating unlocking mechanism of a lock comprising in combination, relatively movable members, a plunger movable relative to one of said members and means associated with said members for moving said plunger through a series of movements.

2. A device for operating unlocking mechanism of a lock comprising in combination, relatively movable members, a reciprocable plunger at one end of one of said members and co-operating means associated with said members operable as the members are moved relative to one another to impart a series of reciprocating movements to said plunger.

3. A device for operating unlocking mechanism of a lock comprising in combination, a barrel member and a relatively reciprocable cap member, a plunger member reciprocable in said barrel member, and means associated with said members operable as the cap member and barrel member are relatively reciprocated to reciprocate said plunger through a series of reciprocations.

4. A device for operating unlocking mechanism of a lock comprising in combination, a barrel member and a relatively reciprocable cap member, a plunger member extending from and reciprocable in said barrel member, and means associated with said members operable as the cap member and barrel member are relatively reciprocated to reciprocate said plunger through a plurality of series of reciprocations.

5. A device for operating unlocking mechanism of a lock comprising in combination, a barrel member, a cap member reciprocable and rotatable on the barrel member, a plunger member reciprocable in said barrel member, means associated with said members operable as the cap and barrel members are reciprocated relative to one another to reciprocate said plunger through a plurality of series of reciprocations, and means to facilitate the selection of one of the plurality of series of reciprocations.

6. A device for operating unlocking mechanism of a lock comprising in combination, a barrel and a relatively reciprocable cap, a plunger slideable in said barrel, releasable engaging means associated with said cap and plunger adapted as the cap is reciprocated relative to the plunger to bring about reciprocation of the plunger by the cap in one direction, means to reciprocate the plunger in an opposite direction, and means to bring about disengagement of said engaging means so the plunger is reciprocated by the cap

and said last-named means through a series of reciprocations.

7. A device for operating unlocking mechanism of a lock comprising in combination, a barrel, a cap reciprocable relative thereto, a plunger reciprocable in said barrel, releasable engaging means associated with said cap and plunger whereby the latter is reciprocated by the former in one direction, means to reciprocate the plunger in an opposite direction, disengaging means including a plurality of devices spaced around said barrel adapted as the cap is reciprocated to disengage said disengaging means more than once during one reciprocation of said cap whereby the plunger is actuated through a series of reciprocating movements.

8. A device for operating unlocking mechanism of a lock comprising in combination, a barrel, a cap reciprocable relative thereto, a plunger reciprocable in said barrel, spring means to reciprocate said plunger in one direction, releasable engaging means associated with said cap and plunger, disengaging means including a plurality of devices spaced around said barrel adapted as the cap is reciprocated to disengage said engaging means more than once during one reciprocation of said cap whereby the plunger is actuated through a series of reciprocating movements, and the said cap being oscillatable to facilitate the selection of certain of said devices.

9. A device for operating unlocking mechanism of a lock comprising in combination, a barrel, a cap reciprocable relative thereto, a plunger reciprocable in said barrel, a guide associated with said plunger, a propeller associated with said cap, releasable engaging parts associated with said propeller and guide whereby the latter is propelled in one direction by the former, means to propel the guide in an opposite direction, and means to engage and disengage said parts as the cap is reciprocated on the barrel whereby the plunger is propelled through a series of reciprocations.

10. A device for operating unlocking mechanism of a lock comprising in combination, a barrel, a cap reciprocable relative thereto, a plunger reciprocable in said barrel, a spring urging said plunger inwardly of said barrel, a guide associated with said plunger having a plurality of longitudinal spaced shoulders, a propeller associated with said cap having a shoulder normally engaging a shoulder of said guide, a key having spaced parts to disengage said shoulders as the cap is reciprocated relative to said barrel whereby the plunger is caused to make a series of outward reciprocations.

11. A device for operating unlocking mechanism of a lock comprising in combination, a barrel, a cap reciprocable relative thereto, a plunger reciprocable in said barrel, a spring urging said plunger inwardly of said barrel, a guide associated with said plunger having a plurality of spaced shoulders, a propeller associated with said cap having a shoulder to engage said shoulders, a plurality of keys each having parts spaced longitudinally of said barrel to disengage said shoulders as the cap is reciprocated relative to said barrel whereby the plunger is caused to make a series of outward reciprocations, the said cap being oscillatable on the barrel to facilitate alignment of the shoulders with any one of said keys whereby a certain series of reciprocations may be selected.

12. A device for operating unlocking mechanism of a lock comprising in combination, a plunger, a support in which the plunger is mov-

able; a spring urging the plunger inwardly of the support, a member movable relative to said support, releasable engaging means associated with said plunger and member adapted to alternately engage and release whereby the plunger is moved through a series of strokes while the member is moved relative to said support.

13. A device for operating unlocking mechanism of a lock comprising in combination, a relatively reciprocable barrel member and cap member, a plunger reciprocable relative to said members, a spring urging the plunger inwardly of said barrel, engageable means associated with said plunger and one of said members and releasing means whereby said plunger is alternately reciprocated and released as said members are reciprocated relative to one another.

14. A device for unlocking mechanism of a lock comprising in combination, relatively reciprocable members, a plunger reciprocable in one of said members, means to urge the plunger in one direction relative to said one member, releasable engaging means associated with the other member and said plunger whereby the plunger is reciprocated by said other member as it is reciprocated relative to the said one member in a direction opposite to said one direction, and releasing means acting on the engaging means during reciprocation of said other member to release the same a plurality of times whereby the plunger is caused to reciprocate a plurality of times in opposite directions.

15. An unlocking device for a lock mechanism comprising in combination, a barrel, a cap reciprocable thereon, a plunger unit reciprocable in the barrel having an end at the outer end of the barrel and provided with engageable parts spaced therealong within the barrel, a propeller in said cap having a part to releasably engage the engageable parts of said unit whereby the end thereof is moved outwardly from the barrel when the cap is moved forwardly of the barrel, a key in the barrel having longitudinally spaced projections engageable by the propeller to release the engaged parts of the propeller and plunger unit, and a spring urging said plunger unit inwardly of the barrel, all adapted and arranged whereby as the cap is reciprocated forwardly of the barrel the end of the plunger unit is caused to reciprocate outwardly and inwardly a plurality of times.

16. An unlocking device for a lock mechanism comprising in combination, a barrel, a cap reciprocable and rotatable thereon, a plunger unit reciprocable in the barrel having an end at the outer end of the barrel and provided with engageable parts spaced therealong within the barrel, a propeller in said cap having a part to releasably engage the engageable parts of said unit whereby the end thereof is moved outwardly from the barrel when the cap is moved forwardly of the barrel, a plurality of keys in the barrel each having longitudinally spaced projections in the path of the propeller to release the engaged parts of propeller and unit, and a spring urging said guide inwardly of the barrel, all adapted and arranged whereby as the cap is reciprocated forwardly of the barrel the end of the plunger unit is caused to reciprocate outwardly and inwardly a plurality of times while the said cap may be rotated to bring the projections of any one of the keys into the path of the propeller.

17. An unlocking device for a lock mechanism comprising in combination, a barrel, a cap reciprocable thereon, a plunger unit reciprocable in the barrel having a plunger end portion projecting therefrom and a guide portion therein, a plurality of spaced shoulders on said guide, a propeller movable relative to the guide having a shoulder for engaging the shoulders of said guide to propel said guide and plunger, a key in said barrel having spaced projections engageable by said propeller and co-operating therewith to disengage said shoulders as the cap is reciprocated forwardly of the barrel, pivotal connections between said cap and propeller whereby the latter may move relative to the former and a spring acting on the propeller to cause it to engage the shoulder thereof with the shoulders of the guide.

18. An unlocking device for a lock mechanism comprising in combination, a barrel, a cap reciprocable thereon, a plunger unit reciprocable in the barrel having a plunger end portion projecting therefrom and a guide portion therein, a plurality of spaced shoulders on said guide, a propeller movable relative to the guide having a shoulder for engaging the shoulders of said guide to propel said guide and plunger, pivotal connections between said cap and propeller, and a key in said barrel having spaced projections engageable by said propeller and co-operating therewith to disengage said shoulders as the cap is reciprocated forwardly of the barrel, the said guide being tube-like in form receiving the end of the propeller and the said shoulders being formed in a wall thereof.

19. An unlocking device for a lock mechanism comprising in combination, a barrel, a key therein having longitudinally spaced projections, a plunger extending outwardly from the forward end of the barrel and reciprocable therein, a spring urging said plunger inwardly of the barrel, a guide fixed to the plunger reciprocable in the barrel having a longitudinal slot, shoulders spaced along said slot, a cap reciprocable on the barrel, a propeller movable on the cap having its forward end in said slot, a projection on the forward end of the propeller and engageable with the projections of said key and a shoulder at the forward end of the propeller engageable with the shoulders of the guide.

20. An unlocking device for a lock mechanism comprising in combination, a barrel, a plunger reciprocable in the end of the barrel, a guide fixed to the plunger reciprocable in the barrel, a spring urging the plunger inwardly of the barrel, a cap reciprocable on the barrel, a propeller hinged at its outer end to the outer end of the cap and disposed therein, the said guide provided with a longitudinal slot and shoulders spaced therealong, the inner end of the propeller disposed in said slot provided with a shoulder engageable with the shoulders of the guide and a prong for engaging the projections of a key, a spring acting on the propeller to position the same so the prong thereof projects outside said slot, and a spring urging the cap rearwardly of the barrel, and a key in said barrel having longitudinally spaced projections engageable by the prong of the propeller to depress the same and disengage the shoulders of said propeller and guide.
